The ornamental design for a sleeve for containers, as shown.

DESCRIPTION

FIG. 1 is a perspective view of a sleeve for containers showing my new design;

FIG. 2 is a top plan view thereof;

FIG. 3 is a front elevational view thereof;

FIG. 4 is a left side elevational view thereof, the right side elevational view being a mirror image thereof;

FIG. 5 is a rear elevational view thereof; and,

FIG. 6 is a bottom plan view thereof.

Portions of the sleeve for containers shown in broken lines in the figures are for illustrative purposes only and form no part of the claimed design.
